Fig. 5.

Fig. 6.

Figure 1 is a front elevational view of a spectacle frame showing my new design;

Figure 2 is a side elevational view thereof;

Figures 3, 4, and 5 are cross-sectional views taken respectively along the lines 3—3, 4—4, and 5—5 of Figure 1; and

Figure 6 is a cross-sectional view taken substantially along the line 6—6 of Figure 2.

The side not shown is the same as the side shown. The top and rear surfaces of the spectacle frame are substantially plain.

I claim:

The ornamental design for a spectacle frame, as shown and described.
